UNITED STATES PATENT OFFICE

OTTO S. FLATH, OF CHICAGO, ILLINOIS

BRACKET

Application filed June 27, 1927. Serial No. 201,594.

My invention relates to a bracket adapted to be oscillatingly supported by the pin of an ordinary door-hinge, thereby obviating the necessity for employing any particular fastening means whereby the bracket is secured in place.

My improved bracket is intended for pendently supporting objects; being more particularly intended for pendently supporting 10 an infant's crib or chair in a manner which will not interfere with the normal use or opening of the door.

The invention also involves a bracket which may be extensible, to adapt it to varying sized 15 objects or cribs of various lengths so as to pendently support the same beyond the door and adjacent wall; the invention also having for its object the provision of a construction possessing the requisite strength and at the 20 same time providing a fastening which may be easily and quickly made and which also involves the element of safety.

The objects and advantages of my invention will be more readily comprehended from 25 the detailed description of the accompanying drawings, wherein—

Figure 1 is a perspective view of one form 30 of my improved bracket shown attached to the ordinary door-hinge.

Figure 2 is a side elevation, partially in section, of the construction shown in Figure 1, shown applied to the ordinary door-hinge.

Figure 3 is a detail sectional view taken on the line 3—3 of Figure 2 looking in the direction of the arrows, with the extension member omitted.

Figure 4 is a detail sectional view taken on the line 4—4 of Figure 2.

Figure 5 is a sectional view taken on the line 5—5 of Figure 2 looking in the direction of the arrows.

Figure 6 is a side elevation of a modified form applied to a door-hinge of which a portion is broken away.

Figure 7 is a detail sectional view taken on the line 7—7 of Figure 6 looking in the direction of the arrows.

Figure 8 is a detail plan of a portion of a

door-hinge, showing a portion of a modified form of my invention.

Figure 9 is a vertical sectional view taken on the line 9—9 of Figure 8.

Figure 10 is a top plan view, with portions 55 broken away, of another modified form of my invention attached to a portion of a door-hinge.

Figure 11 is a side elevation, with parts broken away, of the modification shown in 60 Figure 10.

Figure 12 is a perspective view of another modified form of my improved bracket.

Figure 13 is a side elevation, partially in section, of a further modified form of the invention. 65

Figure 14 is a top plan of the attaching portion of the construction shown in Figure 13.

Figure 15 is a top plan showing the inner or attaching end, illustrating a modification 70 of the type of bracket shown in Figure 13.

My invention relates to a bracket which may be readily applied and supported from the hinge-pin of the ordinary door hinge, thereby obviating the necessity of employing 75 screws or other special means for fastening the bracket in place; my improved bracket being especially intended for pendently supporting objects, such as baby-cribs and the like. My improved brackets are particularly 80 adaptable for use in small apartments where floor space for ordinary cribs or beds is not readily available; the invention at the same time including the elements of strength and

safety which is not obtainable in ordinary 85 brackets adapted to be secured in place by means of screws; a type of bracket wherein the strains are more or less of a pulling nature on the screws; which, by reason of constant vibration, are apt to become loosened. The invention also provides a supporting 90 bracket which may be readily swung against the side of the door or adjacent wall when not in use, without in any way interfering with the door movement. 95

In the exemplification as disclosed in the first four figures of the drawings my improved bracket comprises the triangular main member 20, of suitable metal, having the upper horizontally disposed arm 21 100

which is formed with an inverted T-shape slot-way 22, see Figure 3. The arm 21 is of suitable length and provided on its bottom with the rearwardly declining compression member 23, uniting at its lower end with the hinge engaging base portion 24 of the bracket and which portion is preferably also formed integral with the inner or attaching end of the arm 21 and is disposed at right angles thereto. The base portion 24 on its outer side is concaved to properly fit about the round butt-end of the hinge shown at 25; while the inner end of the top arm 21 extends somewhat beyond the base portion 24, as shown at 26, and is apertured to receive the hinge-pin 27. The slot-way 22 in the arm 21 is provided with an extension rod or plate 28 adapted to slide in said slot-way; the inner end of the plate or rod 28 being provided with an upstanding threaded pin 29 adapted to receive butterfly or other suitable nut 30. The threaded pin or stud 29, before the nut 30 is applied thereto, is preferably provided with a washer as at 31 adapted to bear on the upper surface of arm 21 when nut 30 is screwed into place. It is apparent that by screwing nut 30 downwardly, extension arm or rod 28 will be firmly clamped in its adjusted or distended position. The outer end of rod or arm 28 is preferably provided with an eye-hook 32 shown secured in place by a nut 33 so as to permit rotative movement of the eye-hook, as well as its ready replacement; although it is apparent that the hook may be of different form.

The compression member 23 is also shown provided adjacent to arm 21 with an aperture 34 which is disposed substantially in the same horizontal plane as the eye of the hook 32; and one or more reenforcing webs between the arm 21 and compression member 23 may be employed as shown. It is evident that the aperture 34 therefore provides a separate or additional place of attachment for the suspended object.

The bracket is readily secured in place by simply removing hinge-pin 27, inserting the pin through the aperture in the lip or extension 26 of the top arm 21; it being understood that the aperture in the lip or extension 26 is just sufficient to permit the shank of the hinge-pin to pass therethrough without permitting passage of the head of the pin, as clearly shown in Figure 2. With the hinge-pin re-inserted into the dove-tailing butt portions of the hinge plates, it is evident that my improved bracket will be firmly held against accidental displacement and that the base portion 24 will bear against the butt-end of the hinge and permit the bracket to oscillate laterally into parallel relation with the door or adjacent side wall, without interfering with the proper movement or opening of the door. If it is desired to remove the bracket, this may be readily accomplished

by simply forcing the bracket upwardly which automatically lifts hinge-pin 27 out of its socket. In order to accommodate objects of varying sizes, the rod or slide arm 28 may be adjusted to meet requirements in order to independently support the object without contact with the adjacent wall or door; the object being suspended by suitable rods, wires or other means from the hook 32 and the aperture 34 when desired.

In Figure 6 I illustrate a modification of the construction shown in Figure 1, in that the base or hinge engaging portion 24 is provided with an extension member 35, slotted vertically as shown at 35^a to receive a suitable clamp screw and nut as at 35^b for securing the same to the main hinge engaging portion. The lower end of member 35 is disposed outwardly or rearward as shown at 36, with the rearwardly disposed lower end 36 slotted as shown at 37, in Figure 7, so as to straddle the reduced portion of the bottom hinge knob 38. With this construction, it is apparent that the bracket 39 may be adjusted to hinges of varying vertical width and furthermore that it cannot be lifted out of place until the hinge-pin 27 has been removed; the bracket 39 illustrated in Figure 6 being in every other respect, except for extensible foot portion or member 35, substantially identical with that shown in Figure 1.

The outer end of the upper arm portions of the brackets shown in Figures 1 and 6 are preferably provided with the upstanding lugs 40 which provide abutment for the washer or plate 31 and prevent the too far outward movement of the extension arm 28.

In Figure 8, I show a modification wherein the top arm 41 is provided with the extension 42 disposed in a plane beyond the base portion 43 so as to be disposed across the top of the hinge 25; and the extension 42 being provided with an enlarged or oblong opening 44 of size sufficient to pass readily over the knob of the hinge-pin 27 without necessitating removal of the hinge-pin. The extension 42, at the base of the opening 44, is provided with an inwardly disposed lip 42^a (see Figure 9) adapted to fit beneath the head of the hinge-pin 27 when the bracket is shifted forwardly. The extension 42 also is provided with a transversely disposed tapped opening to receive a set-screw 45 after the bracket has been hung onto the knob of the hinge-pin 27; the tapped opening being disposed transversely at a predetermined point relative to lip 42^a so as to align the set-screw 45 with the reduced portion of the knob of the hinge-pin, when the lip engages in the reduced portion on the opposite side of the knob, as clearly shown in Figure 9. With the set-screw 45 screwed into place and with lip 42^a also in place, it is apparent that accidental jarring of the bracket off the hinge-pin will be prevented

while at the same time oscillatory movement of the bracket will be permitted.

In Figures 10 and 11, I show a further modification of my improved bracket which consists of a metal strap or plate 46 having its end bent back upon itself into loop form, as shown at 47; the strap being of vertical width equivalent to or somewhat greater than the knob of the hinge-pin 27. The loop portion 47 of the strap is made arcuate vertically to fit the curvature of the spherical knob of the hinge-pin; while the short end 48 of the strap is adapted to be disposed substantially parallel with the main portion; the main portion 46 and short arm or end 48 being provided with registering tapped openings to receive a set-screw 49. After the bracket member 46 has been inserted over the knob of the hinge-pin 27, set-screw 49 is screwed into place thereby forcing the two arms of the bracket toward each other into firm clamping relation with the knob of the hinge-pin and thereby preventing its accidental removal because the bottom of the arcuate loop portion 47 of the bracket will engage beneath the head or knob of the pin 27 and prevent upward movement of the bracket, while nevertheless permitting oscillatory movement of the bracket, either about the hinge-pin 27 or through rotation of the hinge-pin in the hinge-plates, depending upon the extent to which set-screw 49 has been screwed into place.

In Figure 12, I show a further embodiment of my invention, consisting of a single piece 35 of metal having a body or web portion 50, the top longitudinal edge whereof is flanged or bent at right angles to the web portion 50 as shown at 51 to constitute the horizontally disposed arm of the bracket. The upper or 40 main arm portion 51 extends rearwardly somewhat beyond the vertically disposed web portion 50, as shown at 52, and is provided with a key-hole opening or slot 53, the enlarged portion whereof, which is disposed 45 forwardly, may pass readily over the knob or head of the hinge-pin 27 while the reduced portion of the slot is adapted to receive the shank of the pin. With this construction, the hinge-pin need not be entirely removed from 50 the hinge, but just sufficiently to permit the extension 52 to come intermediate of the tops of the leaves of the hinge and the base of the knob of the hinge-pin. The outer end of the arm is shown apertured at 54 to receive any 55 suitable fastening means for suspending the object in place; and the lower end of the web or compression portion 50 at its base is shown flanged or bent angularly into horizontal position to provide the rearwardly extending slotted ear 55, which, like the end 36 in the construction shown in Figure 6, is adapted to straddle the reduced part or neck of the finish knob 38 at the bottom of the hinge. This will prevent accidental upward movement of the bracket as well as providing addi-

tional bearing at the lowest point of the compression portion of the bracket.

In Figures 13 and 14, my improved bracket consists of the main bracket member having the horizontally disposed upper arm 56, 70 base portion 57 and compression web or member 58 all formed integral; the outer face of the base portion 57, like that in Figures 1 and 6, being made arcuate or concaved to fit the curvature of the butt-end of the hinge; the upper arm being extended slightly beyond the base portion shown at 59 and apertured to receive hinge-pin 27. The upper arm 56 is provided with a short slot 59 disposed lengthwise of the arm 56 to receive the downwardly bent end 60 of extension arm 61; the lower part of the bent end 60 having laterally disposed ears or lugs 62, 62 adapted to extend beyond the sides of the slot 59, for locking the extension arm 61 in place. It is apparent 80 that with this construction arm 61 must be inserted by disposing the same at right angles to the slot 59 in the main bracket portion 56 so as to have the ears 62, 62 disposed lengthwise of slot 59 in order to permit insertion 85 therethrough.

Instead of having the construction just described and shown in Figures 13 and 14, the main or hinge engaging portion of the bracket as shown in Figure 15 may have the upper arm 63 provided with the longitudinally disposed slot 64, the rear or inner end whereof is extended laterally to opposite sides of the main portion of the slot, as shown at 65, 65, to receive the ears or extensions 62, 62 at 90 the lower end of the downwardly disposed end 60 of the extension arm 61. With the construction shown in Figure 15, the extension arm 61 is inserted into place by having the ears 62 brought into register with the lateral portions 65 of the slot 64; while removal of the extension arm 61 will be prevented as soon as the arm has been moved forwardly in slot 64 where the ears 62 are out of register with the lateral slot portions 65. The upper arm 63, like arm 56 in Figure 13, 100 is apertured at 66 to receive the hinge-pin which must be entirely removed to permit application of the bracket to the hinge.

With all of the constructions shown and described, it is apparent that a very secure supporting bracket is provided, one requiring no special tools or skill in application; a bracket which may be readily applied and which may be swung into parallel relation with the door or adjacent wall without interfering with the door operation, and which at the same time may be easily removed by lifting the attached end upwardly, causing the hinge-pin to move upwardly therewith; or by pulling the hinge-pin out of the hinge-leaves with constructions of the type disclosed in Figure 6 for example.

The invention, which has been exemplified in various forms in the drawings, has been 130

described in terms employed merely as terms of description and not as terms of limitation, as certain modifications may be made without, however, departing from the spirit of my invention.

5 What I claim is:

1. A bracket of the character described comprising, in combination with a door-hinge provided with a removable hinge-pin, a triangular member, the base whereof is adapted to bear against the butt-end of the hinge, while the upper horizontally disposed side of said member is extended beyond said base to lap the upper end of the butt-end of the hinge, said extension being provided with an oblong aperture to receive the head of the hinge-pin, with the base of the extension having a lip disposed forwardly into said aperture to engage beneath the head of the hinge-pin.
- 10 2. In combination with a door-hinge having a vertically disposed hinge-pin provided with an enlarged upper exposed end, a bracket adapted to extend horizontally from the butt-end of the hinge, the inner end whereof is formed to provide an oblong opening to receive the enlarged upper end of the hinge-pin, the rear wall of the opening being curved to fit beneath said hinge-pin enlarged end, and means whereby said bracket may be locked to the hinge-pin.
